FOLDING MECHANISM

John J. Wilkinson, Owego, N. Y., assignor to Howe
Folding Furniture, Inc., New York, N. Y.

Application January 2, 1932, Serial No. 584,309

4 Claims. (Cl. 311—77)

My invention relates to a folding mechanism for card tables, banquet tables, benches, and other like devices wherein a supporting surface or frame is provided with legs which it is desired to render foldable.

The principal object of my invention is to provide a novel folding mechanism for the legs of a supporting surface wherein movement of any one leg thereof, results in simultaneous and synchronous movement of the other legs thereof.

A further object of my invention lies in the provision of a folding mechanism in which the legs are arranged to synchronously fold diagonally from the corners or edges of the supporting surface toward and away from substantially the center of said surface.

Still another object of my invention lies in the provision of such synchronized folding means which permits the free ends of the legs, when moved to the folded position, to overlap each other without interference one with another.

Still another object of my invention lies in the provision of an arrangement of the folding elements which permits such overlapping folding relation of the free ends of the legs in timed relation whereby the folding and the unfolding thereof is accomplished quickly and smoothly and without interference between any of such legs.

A further object of my invention lies in a folding means of the character referred to and comprising essentially a rotatable member positioned substantially centrally of the supporting surface and having link connection with the legs, said legs being synchronously foldable thereby towards and away from such center position.

A still further object of my invention lies in the provision of a resilient releasable locking means for the folding mechanism in the unfolded position of the legs.

It is recognized that heretofore tables have been provided with legs which are foldable diagonally toward and away from the center of the table. It is also recognized that tables have heretofore been provided with automatic folding mechanism for the legs thereof whereby movement of one leg results in synchronous movement of the other legs. Applicant believes himself the first, however, to provide a folding mechanism which permits the folding of legs diagonally toward and away from the table by means of a synchronizing device which causes such folding of all the legs upon the movement of any one thereof.

The objects and advantages in details of construction and operation will be apparent as the description proceeds, reference now being had to the figures of the accompanying drawing forming a part of this application and wherein like reference numerals indicate like parts.

In the drawing: Figure 1 is a bottom plan view of a table, such as a card table, embodying my invention, and showing the legs in partially folded position.

Figure 2 is a side view thereof, certain parts being broken away for clearness of illustration.

Figure 3 is a detail bottom plan view showing the free ends of the legs in completely folded position.

Figure 4 is a detail bottom plan view illustrating the position of the folding mechanism with the legs in completely unfolded position.

Figure 5 is a detail bottom plan view illustrating the position of the folding mechanism with the legs in completely folded position.

The reference character 1 refers to a supporting surface around the edges of which there may be provided the side frame members 2. On the underside of the supporting piece 1 and at each corner thereof, there is provided a pivot pin 3 extending diagonally across the corner and to these pivot pins are pivoted respectively the legs 4, 5, 6 and 7.

Rigidly secured as by the fastening means 8 at a point on the underside of the supporting surface 1 and centrally thereof, is a fixed member 9, which may be in the form of a disk or otherwise, and which is suitably spaced slightly away from the surface 1. Rotatably mounted between the fixed member and the supporting surface 1, for free rotation about the center of the supporting surface is the synchronizing member 10, which may take any desired form or configuration, and which as shown is merely a substantially square flat plate. The shape and form of the members 9 and 10 is immaterial and those shown are intended as illustrative only.

Pivotedly mounted upon the synchronizing member 10 at suitably spaced intervals with respect to each other, and with respect to the center thereof, as will be hereinafter more fully explained, are the pivot members 11, 12, 13 and 14. These pivot members are pivotally secured upon the synchronizing member 10, as by means of the bolts 15 or the like, whereby such pivot members may rotate upon the plate 10. Each of these pivot members is provided with a depending flange 16.

Pivoted at one end to the leg 4 adjacent the pivoted end thereof, as at 17, is a link 18 pivoted at its opposite end to the flange 16 of the pivot member 11. Similarly pivoted at one end to the leg 5, as at 19, is a link 20 pivoted at its opposite end to the flange 16 of the pivot member 12. Similarly pivoted at one end to the leg 6, as at 21, is a link 22 pivoted at its opposite end to the flange 16 of the pivot member 14. Likewise pivoted at one end to the leg 7, as at 23, is the link 24 pivoted at its opposite end to the flange 16 of the pivot member 14.

Thus there is provided an operative connection between each of the legs and the synchronizing member 10. The disposition of the pivot members on the plate 10 for each of the links and corresponding legs is such that the longitudinal position of the link members is slightly off center or tangential to the center pivot of the rotatable synchronizing member 10. Consequently movement of any one leg inwardly towards folding position, results in rotation of the synchronizing member 10 and consequently of the pivot members thereon, resulting in drawing the other links of the folding means inwardly and consequently pulling all of the legs downwardly towards folded position. The converse is also true for if any one leg is moved outwardly from folded toward unfolded position, the link attached to that leg exerts a pull upon the pivot member to which it is attached, thus causing the synchronizing member to rotate in the direction of pull and such movement is thus communicated to the other links and legs whereby all of them move simultaneously.

Inasmuch as the length of the legs is such that when in folded position the free ends thereof must overlap each other centrally of the supporting surface, I have provided means for so timing the folding and unfolding movement thereof that such free ends do not interfere with each other. This timing means consists in the spacing of the pivot members 11, 12, 13 and 14 with respect to the center pivot point in such manner that certain of said legs fold slightly ahead of the others.

It will be noted particularly with reference to Figures 1 and 4 that the pivot members 12 and 14 are spaced closer to the center pivot point of the synchronized member 10 than are the pivot members 11 and 13. Because of this, it will be clear that these pivot members 12 and 14, because they travel on a smaller radius than do the pivot members 11 and 13, will result in a slower movement of the links 20 and 24 and consequently of the legs 5 and 7 than is the case with the pivot members 11 and 13, traveling on a larger radius and therefore causing the links 18 and 22 and consequently the legs 4 and 6 to move more rapidly than the legs 5 and 7. As a result, the legs 4 and 6 will more quickly assume the folded position shown in Figure 3, than will the legs 5 and 7, the free ends of the legs 4 and 6 thus positioning themselves adjacent the supporting surface 1 just prior to the completed inward movement of the free ends of the legs 5 and 7.

It will also be noted that the pivot members 12 and 14 are positioned slightly back of center, that is, back of the center line formed between the pivots 3 of the legs 5 and 7 and the axis of the synchronizing member 10. Thus on the initial folding movement, the braces 20 and 24 must first pass this center before the actual folding of these legs starts. The pivot member 11 and

13, however, are disposed slightly ahead of center with respect to the member 10 and thus start the folding movement of the faster legs 4 and 6 while the braces 20 and 24 are passing center. This contributes largely to the proper timing of the legs so as to avoid interference between them when folded together.

Of course, the oppositely disposed legs are so arranged that they are slightly spaced apart and lie adjacent each other when in folded position.

Thus I have prevented the possibility of any interference between the free ends of the legs when moved to folded position, the timing thereof permitting easy and prompt movement of the free ends of the legs in overlapping position centrally of the supporting surface, the legs 4 and 6 reaching the limit of the folded position just ahead of the legs 5 and 7 due to the difference in the radial movements of the corresponding pivot members to which such legs are connected by means of the links.

In the unfolding operation, the outward movement of any leg which may be grasped by the operator and pulled outwardly, results in simultaneous movement of all the other legs as will be obvious from the foregoing. It will be clear also that due to the fact that the more rapidly moving legs are positioned underneath the slower legs due to the timing arrangement just described, the result is that the free ends of the "faster" legs 4 and 6 assist in the unfolding movement by pressing outwardly upon the free ends of the outside slower legs 5 and 7 at the immediate start of the unfolding operation.

In order that the legs may be releasably locked in unfolded position, there is pivoted at one end to the fixed central member 9 as at 25 a lever 26 provided at its free end with a bent finger piece 27. Secured to this lever as at 28 is one end of a coil spring 29 which stretches across the fixed member 9 and at one side of the central pivot point of the synchronizing member 10, to a pin or other fastening means 30 upon said synchronizing member 10, to which fastening means the opposite end of the spring 29 is attached. The result of this positioning of the spring 29 is to normally urge the synchronizing member 10 to rotate in a direction to unfold the legs.

Pivoted to the lever 26 intermediate its ends, as at 31, is a link 32, the opposite end of which is pivoted to the synchronizing member 10 as at 33. This link 32 is so arranged with respect to the lever 26 and the synchronizing member 10 that when the legs are in their completely unfolded position, as shown in Figure 2, the parts of folding mechanism will have assumed the position shown in Figure 4, and in which the end of the link 32 which is pivoted to the lever 26, will engage with the edge of the fixed center piece 9, and in which position the lever 26 is disposed slightly beyond a center longitudinal alignment with the link 32. In such position the distance between the pivot points 25 and 31 is such as to prevent further inward movement of the lever 26, and because such lever 26 is slightly past center with respect to the link 32, the synchronizing member 10 is thus prevented from accidental or inadvertent rotation in the opposite direction, the spring 29 retaining the lever 26 in such position. When it is desired, however, to release the legs for folding movement, the operator merely rocks the lever 26 on its pivot 25 moving the same past center alignment with the link 32, whereupon the synchronizing

member 10 may be freely rotated in the opposite direction against the tension of the spring 29 by moving the legs and consequently the links connected thereto in the manner heretofore described. During such folding movement, the spring 29 is carried past the pivot point 25 of the lever 26, as shown clearly in Figure 5, and thus exerts a pull upon the lever 26 in the opposite direction, whereby the legs are releasably held in folded position until again moved outwardly, a sufficient distance to rotate the synchronizing member 10 and bring the spring 29 again past the pivot point 25 whereupon the spring again exerts its influence upon the lever in the opposite direction as just described.

Thus there is provided a releasable locking means for the legs in both folded and unfolded position.

Of course, changes may be made in details of construction and arrangement of parts without departing from the spirit and scope of my invention. I do not limit myself, therefore, to the exact form herein shown and described other than by the appended claims.

I claim:

1. A folding mechanism comprising a supporting surface, legs pivoted thereto and foldable toward said surface in overlapping relation, rotatable means on said surface, and means connecting said legs and said means for synchronously folding all of said legs in timed relation upon movement of any leg, said connecting means comprising links and pivot members on said rotatable means, said pivot members being variably spaced on said rotatable means.

2. In a table, a table top, a top-supporting frame, legs pivotally mounted on the frame adjacent the several corners of the table and each adapted to swing diagonally inward to folded position beneath the top, the legs of each diagonally opposite pair being so pivoted on the frame that they will be positioned alongside one another when folded, and means connecting the legs by which movement of one leg to folded

or unfolded position will cause similar movements of the other legs, said means embodying mechanism for causing one pair of diagonally opposed legs to swing inwardly in advance of the other pair, so that the last mentioned pair of legs will fold over the first mentioned pair.

3. In a table, a table top, a top-supporting frame, legs pivotally mounted on the frame adjacent the several corners of the table and each adapted to swing diagonally inward to folded position beneath the top, the legs of each diagonally opposite pair being so pivoted on the frame that they will be positioned alongside one another when folded, and means connecting the legs by which movement of one leg to folded or unfolded position will cause similar movements of the other legs, said means embodying mechanism whereby one pair of diagonally opposed legs is caused to fold over the other pair of legs, and means cooperating with the first mentioned means to simultaneously lock all of the legs in unfolded position.

4. In a table, a table top, a top-supporting frame, legs pivotally mounted on the frame adjacent the several corners of the table and each adapted to swing diagonally inward to folded position beneath the top, the legs of each diagonally opposite pair being so pivoted on the frame that they will be positioned alongside one another when folded, and means connecting the legs by which movement of one leg to folded or unfolded position will cause similar movements of the other legs, said means comprising a plate rotatably mounted beneath the central portion of the frame, and link mechanisms connecting the respective legs with the plate, the pair of link mechanisms for one pair of the diagonally opposed legs being connected with the plate closer to its pivotal axis than the other pair of link mechanisms so that the first mentioned pair of legs will move in more slowly and will fold over the other pair of legs.

JOHN J. WILKINSON.
